CUSHIONING DEVICE FOR ELECTRIC MOTORS

Charles Hugh Duffy, Miami, Fla.

Application May 3, 1941, Serial No. 391,758

14 Claims. (Cl. 308—163)

(Granted under the act of March 3, 1883, as amended April 30, 1928; 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to devices for cushioning or absorbing the shock due to the end-play of shafts, and is particularly adapted for use on the rotor or armature shafts of electric motors, though it will appear from the following specification taken in connection with the accompanying drawing that the device is equally applicable to shafts in general.

Referring to the drawing:

Figure 1 is a side elevation of the rotor and shaft of an electric motor in its end bearings and illustrating the device in operative position on both ends of the rotor shaft.

Figure 2 is a side elevation of the square bushing employed in the device.

Figure 3 is an end elevation of the same.

Figure 4 is an edge elevation of the spring tension-washer assembly.

Figure 5 is a front elevation of the same.

Figure 6 is an end elevation of the round tubular spacer bushing.

Figure 7 is an end elevation of a modified form illustrating the tubular bushing as being square.

Figure 8 is a side elevation of a modified form of the square bushing shown in Figure 2.

Figure 9 is a side elevation of a similar square bushing as used in the modified assembly shown in Figure 10, and

Figure 10 is a side elevation of a modification of the device shown in Figure 1.

Like numerals of reference indicate the same parts throughout the several figures, in which,

1 indicates the rotor or armature of an electric motor, 2 and 3 indicate the end portions of the rotor or armature shaft 4, and 5 and 6 indicate the shaft bearings.

7 indicates the shock cushioning or absorbing device, which includes the square bushing 8; tension washer assembly 9; tubular spacer bushing 10 and thrust washer 11.

In practice, the bearings 5 and 6 are suitably supported in the motor frame or housing in any approved manner. Prior to mounting the rotor or armature shaft in its bearings 5 and 6, a square bushing 8 having a bore 8' of a size to provide a slight press fit on the shaft 4, is positioned on each end portion 2 and 3 of said shaft, and in the example shown in the drawing, placed directly against the sides of the rotor 1. These

square bushings 8 are of such length that the outer ends thereof are spaced from the shaft bearings 5 and 6, as shown in the drawing. The spring-tension-washer assembly 9 which includes two flat washers 9' of suitable material, and a central intermediate spring-tension-washer 9'', either cupped as shown, or of any other appropriate or conventional form, and of any approved spring material, is placed between the two flat washers 9', as shown in Figure 4.

These washers 9' and 9'' are each provided with square holes 9''', so that they may freely move longitudinally over the square bushing 8 but will not rotate thereon. The tubular spacer bushing 10, which may be either round or square, is provided with a bore 10' sufficient to permit the spacer to freely pass over the end of the square bushing 8 and have free longitudinal movement with respect to the square bushing 8. The thrust washer 11 is then placed on the shaft and against the outer end of the spacer bushing 10, so that the inner end of the spacer bushing 10 bears against the outermost flat washer 9' of the spring-tension-washer assembly while the outer end of the spacer bushing 10 abuts the thrust washer 11, as shown in Figure 1.

In operation the device is applied to each end 2 and 3 of the shaft 4, with the thrust washers 11 against the shaft bearings 5 and 6, as in the example shown. Longitudinal movement (end-play) of the shaft in either direction will cause one or the other of the spring-tension-washers 9'' to be compressed between its contacting flat washers 9' and thus cushion or absorb the shock of such longitudinal shaft movement (end-play) which would otherwise occur, and which usually results in a rapid, objectionable hammering noise.

It will be seen that the function of the square bushings 8 pressed on the shaft 4 and of the square holes in the spring-tension-washer assembly 9 is to insure rotation of the spring-tension-washer assembly with the shaft, and thus prevent any cutting action on or injury to the shaft which usually occurs when a spring-tension-washer is mounted directly on the shaft and relative rotation between shaft and spring-tension-washer is permitted. An additional advantage resulting from this construction, is that wear on the tension washer assembly which would result from relative rotation of the washers is entirely eliminated.

If the spacer bushing is square, as shown, this bushing is also caused to rotate with the shaft and tension-washer-assembly 9 so that all relative rotation is localized at the thrust washer,

which is the most favorable place for such rotation, since the thrust washer is in a favorable position to get lubrication from the shaft bearings.

While in the example shown in the drawing, the square bushings 8 and spring-tension-washer assemblies 9 are shown directly abutting the rotor 1, and the thrust washers 11 are shown directly abutting the shaft bearings 5 and 6, it will be understood that the drawing merely illustrated one example of the application of the device to a shaft which is subject to objectionable end-play. In other applications the square bushing 8 and spring-tension-washer assembly 9 may contact any suitable abutment on a shaft, while the thrust washer 11 may contact any suitable abutment on the frame or other stationary structure to which the shaft is applied.

It is also apparent that any desired number of conventional thin flat washers may be applied in connection with the device in order to adjust the length of the same to any particular condition without departing from the spirit of the invention.

For such shafts as do not have a convenient abutment against which the square bushing and spring-tension-washer assembly may bear, the square bushing may itself be provided with an abutment 8" as shown in Figure 8. In such applications the square bushing 8 with its abutment is pressed on the shaft to a predetermined position, the spring-tension-washer assembly 9 is placed on the square bushing and against the abutment 8" on the square bushing 8, and the spacer bushing 10 and thrust washer 11 are assembled in the same relative positions as shown in Figure 1.

In the modified example shown in Figure 10, which illustrates the use of the modified form of square bushing 8, shown in Figure 8, pressed on the shaft to a predetermined position to provide a shoulder abutment 8" for the spring-tension-washer assembly 9. In this example, there is also shown abutting the outer end of the square spacer bushing 10, a shallow square bushing 12 having a shoulder abutment 12" similar to the modified square bushing 8 and its shoulder abutment 8" except that the bore of this square bushing 12 is of a size to permit free longitudinal movement on the shaft, while abutting the flanged abutment 12" of this square bushing 12 is the thrust washer 11.

In operation, the square spacer bushing 10 extends over the end of the square bushing 8 and abuts against the tension washer assembly 9, and also extends over the square bushing 12 and abuts against its flanged abutment 12" so that every element of the assembly rotates with the shaft except the thrust washer 11, and all relative rotation is positively localized at the thrust washer 11.

What I claim is:

1. A device for absorbing or cushioning the end-play of the shafts of electric motors and the like, which includes, in combination with the shaft provided with an abutment thereon, a square bushing having a bore small enough to provide a press fit on the shaft to insure rotation of the square bushing with the shaft, a spring tension-washer assembly mounted on the square bushing and against the abutment on the shaft, the spring-tension washer assembly including two flat washers and an intermediate spring-tension washer adapted for compression between the two flat washers of the assembly, all of the

washers of the spring-tension washer assembly being provided with square holes slightly larger than the square bushing to insure rotation thereof with the square bushing and provide free longitudinal movement thereon, a thrust washer on the shaft and a square tubular spacer bushing having its hole slightly larger than the first mentioned square bushing and positioned over the end of the first mentioned square bushing and between the spring washer assembly and the thrust washer.

5 2. A device for absorbing or cushioning the end-play of the shafts of electric motors and the like, which includes, in combination with the shaft provided with an abutment thereon, a square bushing having a bore small enough to provide a press fit on the shaft to insure rotation of the square bushing with the shaft, a spring-tension washer assembly mounted on the square bushing and against the abutment on the shaft, the spring-tension washer assembly including a spring tension washer and two flat washers, the flat washers being provided with square holes large enough to permit longitudinal 15 movement thereof on the square bushing and to insure rotation thereof with the square bushing, a thrust washer on the shaft and a tubular spacer bushing having a hole large enough to freely pass over the end of the square bushing and between the spring-tension washer assembly and the thrust washer.

20 3. A device for absorbing or cushioning the end-play of the shafts of electric motors and the like which includes, in combination with the shaft, a square bushing mounted on the shaft, a spring tension washer mounted on the square bushing, and provided with a square hole large enough to permit longitudinal movement thereof on the square bushing and to insure rotation thereof with the square bushing, a thrust washer and spacing means between the spring tension washer and the thrust washer.

25 4. A device for absorbing or cushioning the end-play of the shafts of electric motors and the like, which includes, in combination with the shaft, a bushing mounted on the shaft, a spring-tension washer assembly mounted on the bushing, the assembly including a spring-tension washer and two flat washers, said washers having holes large enough to permit longitudinal movement of the washers on the bushing, the said bushing and the holes of the flat washers being shaped to interengage and insure rotation of the flat washers with the said bushing, a thrust washer and means for spacing the spring-tension washer assembly from the thrust washer.

30 5. A device for absorbing or cushioning the end-play of the shafts of electric motors and the like, which includes, in combination with a rotatable and longitudinally movable shaft, a bushing mounted on the shaft, a spring-tension washer mounted on the bushing, the said bushing and the hole in the spring-tension washer being shaped to interengage and insure rotation of the washer with the said bushing, a thrust washer remote from the bushing and mounted on the shaft, and means for spacing the spring tension washer from the thrust washer.

35 6. A device for absorbing or cushioning the end-play of the shafts of electric motors and the like, which includes, in combination with a rotatable and longitudinally movable shaft, a bushing mounted on the shaft, a spring-tension washer assembly mounted on the bushing, a thrust washer remote from the bushing and

mounted on the shaft, and means for spacing the spring-tension washer assembly from the thrust washer.

7. A device for cushioning or absorbing the end-play of the shafts of electric motors and the like, which includes, in combination with the shaft, a square bushing having a bore small enough to provide a press fit on the shaft to insure rotation of the square bushing with the shaft, an abutment on the square bushing, a spring-tension washer assembly mounted on the square bushing and against the abutment thereon, the spring-tension washer assembly including two flat washers and an intermediate spring-tension washer adapted for compression between the two flat washers of the assembly, all of the washers of the spring-tension washer assembly being provided with square holes slightly larger than the square bushing to insure rotation thereof with the square bushing and provide free longitudinal movement thereon, a thrust washer on the shaft, a square bushing adjacent the thrust washer, having a bore larger than the shaft to permit free longitudinal movement thereof on the shaft, an abutment on the square bushing, and a square tubular spacer bushing having its hole slightly larger than the first mentioned square bushing and positioned over the first mentioned square bushing and over the square bushing adjacent the thrust washer and between the spring washer assembly and the abutment on the square bushing adjacent the thrust washer.

8. A device for absorbing or cushioning the end-play of the shafts of electric motors and the like, which includes, in combination with the shaft, a square bushing having a bore small enough to provide a press fit on the shaft to insure rotation of the square bushing with the shaft, an abutment on the square bushing, a spring tension washer assembly mounted on the square bushing and against the abutment thereon, the spring-tension washer assembly including a spring-tension washer and two flat washers, the flat washers being provided with square holes large enough to permit longitudinal movement thereof on the square bushing and to insure rotation thereof with the square bushing, a thrust washer on the shaft, a square bushing adjacent the thrust washer and having a bore large enough to permit free longitudinal movement thereof on the shaft, an abutment on the last mentioned square bushing and a tubular spacer bushing having a hole large enough to freely pass over the first mentioned square bushing and disposed between the spring tension washer assembly and the abutment on the last mentioned square bushing.

9. A device for absorbing or cushioning the end-play of the shafts of electric motors and the like, which includes, in combination with the shaft, a square bushing mounted on the shaft, an abutment on the square bushing, a spring tension washer mounted on the square bushing and provided with a square hole large enough to permit longitudinal movement thereof on the square bushing and to insure rotation thereof with the square bushing, a thrust washer on the shaft, a square bushing adjacent the thrust washer and having a bore large enough to permit longitudi-

nal movement thereof on the shaft, an abutment on the last mentioned square bushing, and spacing means between the spring tension washer and the abutment on the last mentioned square bushing.

- 5 10. A device for absorbing or cushioning the
end-play of the shafts of electric motors and the
like, which includes, in combination with the
shaft, a bushing mounted on the shaft, an abut-
10 ment on the bushing, a spring-tension washer
assembly mounted on the bushing, the assembly
including a spring tension washer and two flat
washers, said washers having holes large enough
15 to permit longitudinal movement of the washers
on the bushing, the said bushing and the holes
of the flat washers being shaped to interengage
and insure rotation of the flat washers with the
said bushing, a thrust washer, a bushing on the
20 shaft adjacent the thrust washer and provided
with an abutment, and means for spacing the
spring-tension washer assembly from the thrust
washer.

11. A device for absorbing or cushioning the
end-play of the shafts of electric motors and the
25 like, which includes, in combination with the
shaft, a bushing fixed on the shaft and rotatable
therewith, an abutment on the bushing, a spring
30 tension washer mounted on the bushing and ro-
tatable with the bushing and the shaft, the said
bushing and the hole in the spring tension washer
being shaped to interengage and insure rotation
35 of the washer with the said bushing a thrust
washer and means for spacing the spring ten-
sion washer from the thrust washer.

12. A device for absorbing or cushioning the
end-play of the shafts of electric motors and the
like, which includes, in combination with the
shaft, a bushing fixed on the shaft and rotatable
40 therewith, an abutment on the bushing, a spring-
tension washer assembly mounted on the bush-
ing, a thrust washer, and means for spacing the
spring-tension washer assembly from the thrust
washer.

13. A device for absorbing or cushioning the
45 end-play of the shafts of electric motors and the
like, which includes, in combination with the
shaft, a bushing fixed on the shaft so as to insure
rotation of the bushing with the shaft, and to
50 prevent longitudinal movement of the bushing
with respect to the shaft, a spring tension washer
assembly mounted on the bushing and rotatable
therewith, and means coacting with the spring
55 washer assembly to cause compression of the
spring tension washer of the assembly upon
longitudinal movement of the shaft in one direc-
tion.

14. A device for absorbing or cushioning the
end-play of the shafts of electric motors and the
like, which includes, in combination with the
60 shaft, a bushing fixed on the shaft so as to insure
rotation of the bushing with the shaft, and to
prevent longitudinal movement of the bushing
with respect to the shaft, a spring tension washer
65 mounted on the bushing and rotatable therewith,
and means coacting with the spring-tension wash-
er to cause the same to be compressed upon longi-
tudinal movement of the shaft in one direction.

CHARLES HUGH DUFFY.
